UNITED STATES PATENT OFFICE.

LEE D. SCHROY, ERY A. LUNDGREN, AND ANDREW J. FLEITER, OF AKRON, OHIO.

DESIGN FOR A BATTERY BOX.

Application filed January 21, 1924. Serial No. 8,365. Term of patent 14 years.

To all whom it may concern:

Be it known that we, LEE D. SCHROY, ERY A. LUNDGREN, and ANDREW J. FLEITER, citizens of the United States, residing at Akron, in the county of Summit and State of Ohio, have invented a new, original, and ornamental Design for a Battery Box, of which the following is a specification, reference being had to the accompanying drawings, forming a part thereof.

In the drawings:

Figure 1 is a side view of the box;

Figure 2 is an end view thereof.

We claim:

The ornamental design for a battery box, as shown.

LEE D. SCHROY.
ERY A. LUNDGREN.
ANDREW J. FLEITER.
